UNITED STATES PATENT OFFICE.

FRANK M. RUTE, OF STERLING, ILLINOIS, ASSIGNOR TO RUSSELL, BURDSALL & WARD BOLT & NUT COMPANY, OF PORT CHESTER, NEW YORK, A CORPORATION OF NEW YORK.

SWAGING MACHINE.

Application filed July 30, 1927. Serial No. 209,431.

This invention relates to a machine which is particularly designed for, by a swaging process, producing pointed lag screw blanks although it is equally adapted 5 for forming blanks for other large screws and bolts with pointed or rounded ends.

In the commercial production of such screws and bolts in large quantities it is customary to roll the threads rather than cut 10 the threads on the blanks. As the threaded section of the screw should not be larger in diameter than the shank section which is not threaded, and rolling threads tends to increase the diameter, the section of the 15 blank which is to be thus threaded is reduced to less diameter than the shank section so that when the thread is rolled it will have the desired diameter.

The object of the present invention is to 20 provide an automatic machine which will rapidly produce pointed lag screws and bolt blanks of accurate size and condition to be immediately threaded by a thread rolling machine.

25 In the embodiment of the invention illustrated headed blanks of circular cross-section and slightly shorter than the finished articles, are fed one at a time to opened jaws mounted on the end of a vertically floating spindle. When the jaws are closed 30 on the blanks the spindle is dropped to lower the end of the blank into the path of two pairs of rotating dies which reduce the section to be threaded and point the end. 35 After one pair of dies has acted on two opposite sides of the blank the spindle is raised, then rotated 90° and again lowered so that the second pair of dies will act upon the other sides of the blank and will reduce 40 it uniformly and retain its circular cross-section. The spindle is again raised and rotated 90° and the jaws opened to discharge the swaged blank and receive a following blank.

45 Fig. 1 of the accompanying drawings shows a plan of so much of the mechanism of the machine as is necessary to an understanding of the invention, the machine frame being omitted. Fig. 2 shows on 50 larger scale a section of the spindle with the blank carrying jaws opened. Fig. 3 shows a side elevation of the spindle and the mechanism for lifting, lowering and rotating it and opening the jaws. Fig. 4 55 shows a front elevation of the dies and

spindle with a blank between one pair of dies. Fig. 5 is a cross-section on the plane indicated by the dotted line 5—5 on Fig. 4 showing the rack and pinion for rotating the spindle. Fig. 6 shows the jaws at the 60 end of the spindle closed upon a blank, and the means for closing the jaws. Fig. 7 shows a plan of the dies and the means for 65 rotating them. Fig. 8 shows the means which connects the driving mechanism with the shaft which carries the cams that raise and lower and rotate the spindle. Fig. 9 is a front elevation of a pair of the dies with 70 portions broken away. Fig. 10 is a top view of a pair of the dies with portions broken 75 away. Fig. 11 shows the face of one of the dies and Fig. 12 shows the face of the other die of each pair. Fig. 13 shows a blank before it is submitted to the action of this machine. Fig. 14 shows a blank after 80 it has been operated upon in this machine. Fig. 15 shows a lag screw made from one of these blanks.

With the mechanism illustrated the headed blank 1 is swaged by two sets of 80 rotatable dies 3 and 4 which elongate and reduce the diameter of the section 5 and form the point 6, which section and point are to be subsequently provided with the thread 7. (Figs. 13-15.) The dies are set in 85 pockets in the heads 8 at the front ends of parallel shafts 9 and 10 that are mounted in bearings in the frame 11. The die shafts are provided with intermeshing gears 12 and 13 so that they will rotate in unison 90 and one of the shafts has a driving pulley 14 (Fig. 7). The perimeters of the dies are formed on arcs concentric with the axis of the shafts, and the die cavities, one-half of which is in each die of a set, are similarly 95 curved. It is preferred, for the purpose of reducing the cost of manufacture and also to permit the ready substitution of dies which will form differently shaped points, to have each die made of two members, one, 100 15, containing the curved and semi-circular cavity 16 for swaging the body of the blank, and the other, 17, having a conical cavity 18 for forming the point. (Figs. 9-12.)

The blank 1 is fed by any suitable means 105 to jaws 19 that are detachably fastened to arms 20 which are held by pivots 21 in an opening in the head 22 at the lower end of the spindle 23. The spindle is lowered, raised, and rotated so that first one set of 110

dies and then the other set of dies act upon the blank for reducing and pointing the section to be threaded. These arms above the pivots have shoulders 24 and at their upper ends carry rolls 25. The spindle is tubular and contains a rod 26 that is normally held raised by a spring 27 that thrusts between a collar 28 in the spindle and a sleeve 29 fastened to the upper end of the rod. (Fig. 2.)

Attached to the lower end of this rod is a double wedge 30 that is adapted, as the rod is raised by the thrust of the spring, to engage the rolls 25 and spread the upper ends of the arms and cause the jaws to close as illustrated in Fig. 6. When the rod is forced down against the thrust of the spring its lower end engages the shoulders 24 and causes the jaws to open as illustrated in Fig. 2. Normally the jaws remain closed under the thrust of the spring, but when the spindle is raised they are opened for discharging a swaged blank and receiving another, by the engagement with the screw 31 threaded into the sleeve attached to the upper end of the rod, of the lower end of a screw 32 in the front end of a lever 33. (Fig. 2.) This lever is mounted on a pivot 34 in the frame and its rear end carries a roll 35 which is engaged by a cam 36 on the cam shaft 37. (Fig. 3.) This cam is timed so that the jaws are opened at every alternate rise of the spindle.

A collar 38 is fastened to the spindle and engaging with this collar is the forked end of a lever 39 which is mounted on the pivot 40 and has a roll 41 that is engaged by a cam 42 on the cam shaft 37. This cam is shaped to lift the spindle twice during each rotation of the cam shaft. (Fig. 3.)

Splined on the spindle is a gear 43, the hub of which is rotatably held in a bearing in the frame. The spindle is free to reciprocate vertically through this gear but is rotated thereby. Engaging with the gear 43 is a rack 44. (Fig. 5.) This rack moves horizontally through the frame and at its rear end is connected by a link 45 with an arm 46 that forms a part of the lever 47 which is pivoted at 48 and bears a roll 49 engaged by the cam 50 on the cam shaft. (Fig. 3.) The arm 46 is held in engagement with the lever 47 by a spring 51, and the roll 49 on the lever is held against the cam by a spring 52. This cam 50 is timed so as to, through the lever and rack and gear, oscillate the spindle on its axis 90° at each upward movement of the spindle. The elastic connection between the arm and the lever allows the parts to yield should any obstruction prevent the spindle from rotating.

The cam shaft on one end has a bevel gear 53 that engages with a bevel gear 54 on the upper end of a vertical shaft 55. (Figs. 1 and 8.) This vertical shaft at its lower end has a spiral gear 56 that is engaged by a spiral gear 57 on the die shaft 10, (Figs. 7-8), which through the gears 12, 13 is driven by the pulley 14.

The cams are so timed that the spindle 23 is raised and the upper end of the rod 26 is engaged by the lever 33 and the jaws 19 opened by the lower end of the rod. After a blank has been placed between the jaws, the rod in the spindle is lifted by the spring 27 and the wedge 30 closes the jaws so as to hold the blank. The spindle then drops, carrying the lower end of the blank into the path of the dies. One set of the swaging dies comes around and reduces and elongates the blank and at the same time points the end of the blank. After one set of dies has acted on two opposite sides of the blank the spindle is raised and rotated 90° and then allowed to drop down in time for the second set of dies to engage the opposite sides of the blank and complete the swaging and pointing. Following this the spindle rises and the jaws are opened to allow the blank which has been swaged on both sides to be removed. The spindle is then rotated back 90° and the jaws opened for receiving the following blank. As the dies roll together and operate upon the blank they lift the blank and spindle. The lifting cam is so timed that the lever 33 follows the spindle up, and after the blank passes above the dies the cam and lever lift the spindle still further.

By the mechanism described blanks for lag screws and bolts may be swaged very rapidly and produced in condition for subsequently rolling threads upon the swaged and pointed sections. With each die made up of two members, the members which produce the points can be cheaply made, and different pointing dies with various shapes may be readily substituted for producing the desired ends of the blanks.

The method of swaging described accurately reduces the sections of the blanks which will be increased when they are threaded in the thread rolling machine and at the same time points the blanks so that they are in condition to be immediately introduced into the thread roller, thus eliminating the use of the independent pointing machine previously used.

The invention claimed is:

1. A machine for swaging headed blanks which comprises a pair of rotatable heads, each head carrying two sets of dies, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the

dies twice during each rotation of the heads, mechanism for rotating the spindle on its longitudinal axis 90° on each upward movement of the spindle, fingers carried by the spindle and adapted to grip the blanks by their heads, and mechanism for opening and closing said fingers on each alternate upward movement of the spindle.

2. A machine for swaging headed blanks

10 which comprises a pair of rotatable heads, each head carrying two sets of dies that have semi-circular and semi-conical cavities, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads, mechanism for rotating the spindle on its longitudinal axis 90° on each upward movement of the spindle, fingers carried by the spindle and adapted to grip the blanks by their heads, and mechanism for opening and closing said fingers on each alternate upward movement of the spindle.

3. A machine for swaging headed blanks

which comprises a pair of rotatable heads, each head carrying two sets of dies and each set of dies being formed of two independently detachable members, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads, mechanism for rotating the spindle on its longitudinal axis 90° on each upward movement of the spindle, fingers carried by the spindle and adapted to grip the blanks by their heads, and mechanism for opening and closing said fingers on each alternate upward movement of the spindle.

4. A machine for swaging headed blanks

which comprises a pair of rotatable heads, each head carrying two sets of dies, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads, means adapted to lift the spindle and permit the spindle to drop by gravity, mechanism for rotating the spindle on its longitudinal axis 90° on each upward movement of the spindle, fingers carried by the spindle and adapted to grip the blanks by their heads, and mechanism for opening and closing said fingers on each alternate upward movement of the spindle.

ing said fingers on each alternate upward movement of the spindle.

5. A machine for swaging headed blanks which comprises a pair of rotatable heads, each head carrying two sets of dies, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads, mechanism for rotating the spindle on its longitudinal axis 90° on each upward movement of the spindle, fingers carried by the spindle and adapted to grip the blanks by their heads, a spring normally holding the fingers closed, and mechanism engaged on each alternate upward movement of the spindle for opening the fingers.

6. A machine for swaging headed blanks which comprises a pair of rotatable heads, each head carrying two sets of dies, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads, mechanism for rotating the spindle on its longitudinal axis 90° on each upward movement of the spindle, fingers carried by the spindle and adapted to grip the blanks by their heads, a spring normally holding the fingers closed, a rod extending through the spindle, and mechanism engaging said rod at each alternate upward movement of the spindle and causing it to open said fingers.

7. A machine for swaging headed blanks which comprises a pair of rotatable heads, each head carrying two sets of dies, all of which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads, mechanism for rotating the spindle on its longitudinal axis 90° on each upward movement of the spindle, fingers carried by the spindle and adapted to grip the blanks by their heads, a rod extending through the spindle, a wedge on said rod adapted to open and close said fingers, and means for reciprocating said rod on each alternate upward movement of the spindle.

8. A machine for swaging headed blanks which comprises a pair of rotatable heads carrying a plurality of dies that have semi-circular and semi-conical cavities, all of

which dies are mounted to revolve in the same vertical plane which is transverse to the axis of revolution of the dies, mechanism for rotating the heads so that the complementary dies will coact on the blanks on their upward travel, a spindle movable vertically above and toward and from the dies twice during each rotation of the heads,

mechanism for rotating the spindle on its longitudinal axis 90° on each upward movement of the spindle, fingers carried by the spindle and adapted to grip the blanks by their heads, and mechanism for opening and closing said fingers on each alternate upward movement of the spindle.

FRANK M. RUTH.
